C. E. NELSON,
PRINTING TELEGRAPH APPARATUS,
APPLICATION FILED APR. 18, 1914.

1,205,248.

Patented Nov. 21, 1916.

UNITED STATES PATENT OFFICE

CARL ERIC NELSON, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

PRINTING-TELEGRAPH APPARATUS.

1,205,248.

Specification of Letters Patent. Patented Nov. 21, 1916.

Application filed April 18, 1914. Serial No. 832,744.

To all whom it may concern:

Be it known that I, CARL ERIC NELSON, a citizen of the United States, residing at Wilkinsburg, in the county of Allegheny 5 and State of Pennsylvania, have invented certain new and useful Improvements in Printing - Telegraph Apparatus, of which the following is a specification.

My invention relates to printing telegraph 10 apparatus, and particularly to the connections for the selecting magnets of a home recording receiver.

My invention is especially well adapted to apparatus which is operated on the duplex 15 principle, although it is not limited to this particular adaptation.

I will describe one form of apparatus embodying my invention, and will then point out the novel features thereof in claims.

20 The accompanying drawing is a view, partly diagrammatic, showing one form of apparatus embodying my invention.

Referring to the drawing, the apparatus here shown is located at one station and is 25 connected with a telegraph line L which extends to another station where it is connected with other apparatus which may be similar to that shown in the drawing. The apparatus here shown is adapted to duplex 30 operation, that is, the simultaneous transmission of two messages over the line L in opposite directions. Current is supplied to the line L from batteries B and B', and the supply of this current is controlled by a 35 transmitting relay R^T, which in turn is controlled by a local circuit governed by a transmitting sunflower S^T and contacts C operated by a transmitting key K. The outgoing signals transmitted by key K are recorded 40 on a home recording receiver comprising a plurality of selector magnets M^T, which receiver may be of any suitable type, such for example as the type shown in United States Patent No. 1090367, granted to J. E. Wright 45 on March 17, 1914, for translator for printing telegraph systems. For the sake of simplicity I have omitted from the present drawing all parts of this receiver except the selector magnets M^T. Incoming signals received 50 from the line L control a receiving relay R^R which governs a local circuit including a receiving sunflower S^R and telegraph receiver comprising a plurality of selector magnets M^R; this receiver may be 55 similar to the home recording receiver just

mentioned, and for the same reason as just explained, I have omitted from the drawing all parts of this receiver except the selector magnets M^R.

Since the apparatus here shown is adapted 60 to duplex operation, the circuits are so arranged that the receiving relay R^R is affected by incoming signal impulses but not by outgoing impulses. This selective operation may be accomplished in any suitable 65 manner; as here shown, it is accomplished by an inductive resistance 10, and an artificial line 11 comprising a resistance 11^a and condensers 11^b connected with ground. The terminals of winding 10 are connected 70 respectively with the telegraph line L and the artificial line 11, and the middle point of this winding is connected with a wire 12 to which current is supplied by batteries B, B'. The terminals of the winding of the receiving relay R^R are connected with lines L and 75 11 respectively. With this construction, outgoing current impulses from batteries B, B' divide at the middle point of winding 10 and pass through the halves of this winding 80 in opposite directions; they then pass equally through the two lines L and 11 so that as far as these outgoing impulses are concerned the terminals of relay R^R are of the same potential and this relay is therefore not affected thereby. Incoming current impulses on line L, however, have two 85 multiple paths to ground, viz., through winding 10 and through relay R^R, and because of the impedance of winding 10, a 90 sufficient proportion of this current passes through relay R^R to cause operation thereof.

The receiving sunflower S^R comprises as usual a frame carrying a plurality of fixed contact plates 13, six of which are electrically connected with the six magnets M^R respectively of the incoming signal receiver. A wiper 14 is mounted frictionally on a shaft 15 which rotates constantly in the direction indicated by the arrow. This wiper is restrained from rotation by a hook armature 17 controlled by an electromagnet 16. As is well understood, the first impulse of an incoming signal momentarily energizes this magnet which then releases wiper 14 so that the latter makes one revolution, passing over contact plates 13 successively and thereby connecting magnets M^R successively with a wire 18 so that one or more of these magnets 95 will be energized from a battery B^R depend- 100 105 110

ing on the combination of impulses forming the signal. The circuit for releasing magnet 16 is from battery B^3 through contact 19 of relay R^R , wire 18, brush 20, wiper 14, 5 contact plate 13^a, wire 21, magnet 16 wire 22 to ground G. The circuit for a magnet M^R is the same as that just traced to and including wiper 14, then through a contact plate 13 and the corresponding magnet M^R to 10 ground.

The signal transmitting key K is pivotally mounted at 24 and is biased to the raised position by a spring 28. When depressed it moves a bar 23 which is mounted to reciprocate in guides 25. It is understood that this key K is one of a plurality of similar keys embodied in a keyboard, each of which moves a bar similar to the bar 23. The contact fingers C are pivoted at points 26 15 and are biased to the open position, that is, away from the corresponding contact C', by springs 40. Each finger is provided with a rod 27 which extends laterally under all of the bars 23, and each bar 23 is provided 20 with one or more downwardly-projecting lips 23^a which engage with the corresponding rod or rods 27 when the bar is moved by the key and thereby close one or more of contacts C. It is understood that, as usual, the several bars 23 are provided with different combinations of lips 23^a, so that different combinations of contacts C are closed according to the key which is depressed.

The transmitting sunflower S^T is similar 35 to sunflower S^R except that shaft 15^a rotates in the opposite direction as indicated by the arrow. Wiper 14^a is in this case restrained from rotation by a stop 29 pivoted at 29^a and connected by a rod 30, with a lever 31 pivoted at 31^a. A universal bar 32 extends laterally under all of the keys K and operates the lever 31, so that the depression of any key depresses bar 32 and lever 31 and thereby releases wiper 14^a.

45 The fixed contact member C' with which each contact C engages is connected by a wire 33 with one of the plates 13 of sunflower S^T , and each contact C is connected by a wire 34 with a selector magnet M^T of the 50 home recording receiver hereinbefore mentioned. It will be seen, therefore, that each selector magnet of the home recording receiver is in series with a contact C—C' of

the transmitting device so that this home recording receiver records the signals which 55 are transmitted over the line. By connecting the magnets M^T in this manner I avoid the necessity for a separate sunflower for the home recording receiver and thus simplifying the apparatus. This is an important 60 feature of my invention.

When key K is depressed it closes a certain combination of contacts C and also releases wiper 14^a which then makes one revolution. As the wiper touches plate 13^b it 65 closes a circuit for relay R^T from battery B^4 through wire 35, relay R^T , wire 36, brush 20^a, wiper 14^a, plate 13^b, wire 37, resistance 38, wire 39 to ground G. Relay R^T is thus operated to send a positive impulse over line 70 L which energizes the receiving relay at the other station thereby operating the magnet corresponding to magnet 16 so that the receiving sunflower at said other station is released. Then as the wiper 14^a touches the 75 several plates 13 successively it causes a certain group of magnets M^T to be energized according to the group of contacts C which are closed, and also causes successive operations of relay R^T , thereby sending a corresponding signal over the line L.

Having thus described my invention, what I claim is:

Printing telegraph apparatus comprising a keyboard comprising a plurality of keys 85 and a plurality of circuit controlling contacts the number of contacts being less than the number of keys, a source of current, a transmitting sunflower for connecting said contacts in turn with said source and tending 90 normally to rotate; means controlled by each key for closing a predetermined combination of said contacts when the key is depressed, means controlled by each key when depressed for releasing said sunflower, and a home 95 recording receiver comprising a plurality of selector magnets, each of said magnets being connected in series with one of said contacts.

In testimony whereof I affix my signature 100 in presence of two witnesses.

CARL ERIC NELSON.
